UNITED STATES PATENT OFFICE.

WILLIAM LAWLOR SMITH, OF NEW YORK, N. Y.

APPARATUS FOR IMPREGNATING WOOD.

SPECIFICATION forming part of Letters Patent No. 711,080, dated October 14, 1902.

Application filed February 1, 1902. Serial No. 92,203. (No model.)

To all whom it may concern:

Be it known that I, WILLIAM LAWLOR SMITH, a citizen of the United States, and a resident of the city of New York, Ravenswood, borough of Queens, in the county of Queens and State of New York, have invented a new and Improved Apparatus for Impregnating Wood with Solution, of which the following is a full, clear, and exact description.

This invention relates particularly to apparatus for impregnating wood with a fireproofing solution; and the object is to provide a simple apparatus by means of which the wood may be rapidly treated under high pressure and having means for regulating the device to the pressure desired, and, further, to provide, in connection with the apparatus, an auxiliary or testing cylinder in which comparatively small strips of wood may be placed and subjected to the same treatment as the large timbers in the main cylinder, so that the treatment may at times be observed by removing the wood from the auxiliary cylinder, thus obviating the trouble, time, and expense of drawing off the large amount of solution in the main cylinder and removing the wood therefrom.

I will describe an apparatus for impregnating wood with solution, embodying my invention, and then point out the novel features in the appended claims.

Reference is to be had to the accompanying drawing, forming a part of this specification, in which the figure shows an apparatus embodying my invention.

Referring to the drawing, 1 designates the dome of a main cylinder in which the wood to be treated is placed and which it is not deemed necessary to show herein. A pipe 2 leads from a tank containing solution and connects with a pump 3, from which a pipe 4 leads into the dome 1. Arranged in this pipe 4 is a check-valve 5. The pipe 4 is also provided with a cut-off valve 6, and in an upward extension 7 is arranged a safety-valve 8, which may be regulated to any desired pressure—that is, it is to be arranged to open and permit the escape of liquid should the pressure reach above a certain point. A relief or discharge pipe 9, provided with a valve 9^a, leads from the apparatus. As here shown, the said

pipe has connection with the pipe 4, and it also has connection through the branches 10 and 11 with the suction-pipe 2. In this branch 55 11 of the relief-pipe is a cut-off valve 11^a and a check-valve 12. This pipe 9 also communicates with the casing of the safety-valve, and continued from the portion 10 of said relief-pipe is a pipe 13, which discharges into a 60 tub 14, from which a valved pipe 15 leads into the suction-pipe 2. This extension 13 is provided with a valve 16, which may be closed during a certain operation of the apparatus and opened when liquid is to be discharged into the tub 14. The tub may be prevented from overflowing by means of a float-valve 17, arranged therein and designed to engage in the outlet of the pipe 13. The pipe 15 is also provided with a cut-off valve 18. 70

Having connection with the apparatus at any suitable point is an auxiliary or testing cylinder 19. As here shown, this cylinder 19 connects with the relief-pipe 9 by means of a tube 20, having a valve 20^a. This cylinder 19 will have a removable end or ends, so that material may be passed into and out of the same. 75

In operation after placing the wood to be treated in the main cylinder solution is to be 80 pumped into the cylinder in the usual manner, and at this time the valve in the pipe 9 and the valve 16 will be opened, so as to permit the escape of air from the cylinder while filling the same. Before it is completely 85 filled, however, the said valves are to be closed, so that there will be a cushion of air in the dome. After filling the cylinder, as above mentioned, the valve 6 is to be opened, and the pump 3 while in operation will draw 90 solution from the solution-tank and force it through the pipe 4 and into the dome, consequently producing a pressure on the liquid already within the cylinder, and this operation will be kept up for a considerable length 95 of time—say six or seven hours—until the wood becomes sufficiently impregnated or saturated, and this may be ascertained by removing a piece of wood from the auxiliary cylinder 19, the pressure of liquid in which 100 is equal to that of the liquid in the main cylinder.

To relieve the pressure after the operation, the valve in the pipe 9 is to be opened, as is

also the valve in the pipe-section 11. The high pressure within the operating or main cylinder will cause a greater portion of the liquid to be forced out through the pipes 9, 5 10, and 11 and back through the pipe 2 to the solution-tank. The remainder of the solution may be drawn out from the bottom of the main cylinder.

It may be desired to draw out the liquid 10 through the pipe-section 13. At this time the valve in the pipe 11 must be closed and the valve 16 opened. The liquid will then run into the tub 14 and thence through the pipe 2 to the solution-tank.

15 Having thus described my invention, I claim as new and desire to secure by Letters Patent—

1. In an apparatus of the character described, a suction-pipe, a pump having connection with said suction-pipe, a pipe leading from the pump into a receptacle for containing wood to be treated, a relief-pipe for the receptacle discharging into the suction-pipe, and an auxiliary testing-cylinder having connection with the relief-pipe, substantially as 25 specified.

2. In an apparatus of the character described, a suction-pipe, a pump having connection with said suction-pipe, a pipe leading 30 from the pump into a receptacle for containing wood to be treated, a check-valve in said last-named pipe, and a relief-pipe for the receptacle and discharging into the suction-pipe, substantially as specified.

3. In an apparatus of the character de- 35 scribed, a suction-pipe, a pump with which the pipe connects, a pipe leading from the pump into a receptacle for material to be treated, a safety-valve for said pipe, a check-valve in said pipe, and a relief-pipe leading 40 from said pipe to the suction-pipe, substantially as specified.

4. In an apparatus of the character de- 45 scribed, a suction-pipe, a pump with which the suction-pipe connects, a pipe leading 50 from the pump to a receptacle for material to be treated, a check-valve in said last-named pipe, a relief-pipe leading from said last-named pipe and connected with the suction-pipe, and a check-valve in said relief- 55 pipe, substantially as specified.

5. In an apparatus of the character de- 55 scribed, a suction-pipe, a pump with which said pipe connects, a pipe leading from the pump to a receptacle for material to be treated, a check-valve in said last-named pipe, a safety-valve in said pipe, a relief-pipe dis- 60 charging into the suction-pipe, a cut-off valve in said relief-pipe, and a check-valve in said relief-pipe, substantially as specified. 60

In testimony whereof I have signed my name to this specification in the presence of two subscribing witnesses.

WILLIAM LAWLOR SMITH.
